Edward N. Pageau,
ATTORNEY.

UNITED STATES PATENT OFFICE.

JOHN D. TEMPLETON, OF DETROIT, MICHIGAN.

MUFFLER.

Application filed March 6, 1924. Serial No. 697,174.

To all whom it may concern:

Be it known that I, JOHN D. TEMPLETON, a citizen of the United States, and residing at Detroit, in the county of Wayne and State of Michigan, have invented a new and Improved Muffler, of which the following is a specification.

This invention relates to means for causing the individual discharges of burnt gases from internal combustion engines to be retarded and to be elongated in such a manner that they will join so that instead of escaping from the ultimate discharge aperture as individual amounts under considerable pressure, these gases will issue therefrom in a continuous stream under very light pressure, the usual noise incident to the explosions and explosive discharges of the gases being eliminated; and the object 20 of this invention is to produce a simple and effective mechanism of this character which can be mounted directly in the exhaust pipe of an internal combustion engine and thus reduce the expense incident to the construction of mufflers now in use.

This invention consists in combination with a cylindrical tube through which the exhaust of an internal combustion engine escapes, of an insert formed of sheet metal 30 adapted to constitute a central diaphragm extending longitudinally of the exhaust pipe and wings extending laterally from the central diaphragm along lines which are diagonal to the edges of said diaphragm, said wings being so spaced and positioned that the exhaust gases passing along said diaphragm will be caused to whirl or follow helical paths, thereby being thrown or pressed against the outer casing by centrifugal force, resulting in the giving up to this outer casing of a large percentage of the heat units, and further resulting in a reduction of pressure within the muffler portion of said exhaust pipe and thereby also reducing 40 the back pressure of the engine.

This invention further consists in the details of construction illustrated in the accompanying drawings and particularly pointed out in the claims.

50 In the drawings, Fig. 1 is an elevation of an internal combustion engine indicating my improved sound reducing mechanism installed in the exhaust pipe thereof. Fig. 2 is an elevation of an intake manifold where- 55 in the same mechanism is installed to cause a thorough mixture of the fuel with the air.

Fig. 3 is a blank for the insert embodying my invention. Fig. 4 is a plan thereof after the wings have been brought into proper position. Fig. 5 is an end elevation and Fig. 6 a side elevation of the same. Fig. 7 is a view similar to Fig. 5 with the wings perforated.

Similar reference characters refer to like parts throughout the several views.

The fundamental idea of all mufflers for internal combustion engines is to provide means to cause the individual discharges of gases resulting from the explosions of the fuel to blend or join before passing into the open air so as to eliminate the noises incident to the exhaust of these gases. The ordinary way to obtain this result is to provide a container of sufficient size to hold a number of these discharges, and baffles and other obstructions are usually provided to retard the flow of the burnt gases through the muffler. The larger sizes of these mufflers make for large radiating surfaces which in turn cause the gases to cool rapidly and reduce in pressure and so avoid excessive back pressures.

These mufflers weigh from six to twenty-five pounds and cost from forty-five cents up to nearly three dollars. The present invention provides a small strip of sheet metal weighing only a few ounces and costing very little, which can be slipped into the exhaust pipe of the engine, which effectively eliminates the noise of the explosions, and which causes very little back pressure.

When gases under rapidly varying pressures pass through a conduit and portions of the gases under higher pressures are mixed with portions under lower pressures, a stream of gas under practically uniform pressure is obtained. When gases impinge upon surfaces which are at oblique angles to the path of the gases, the speed of the gases is only moderately reduced.

Referring now to Figs. 1 and 3 to 7 inclusive, an engine 1 is shown conventionally provided with an intake manifold 2 and an exhaust manifold 3 connecting to an exhaust pipe 4 having a horizontal portion 5. This exhaust conduit is shown to be cylindrical but the present invention is not limited to conduits of cylindrical form but may be used with those of any other desired cross section. In ordinary automobile constructions a muffler is connected to the portion 5 of the exhaust conduit for the purpose

of causing the separate discharges of exhaust gases to unite, but I have found that such construction is unnecessary as it is possible to use any desired portion of the exhaust conduit for this purpose. I have found that by inserting a properly sheared and bent strip of sheet metal having a length of from eighteen to twenty-four inches in the exhaust conduit of the smaller 10 types of engines used on automobiles which are provided with exhaust conduits of one and three-eighths inches internal diameters, that the desired effect is produced. A longer strip may be used with larger engines in order to obtain the same degree of noiselessness of operation. It must be understood that shorter strips do not have the same desirable effects as the longer strips.

In Fig. 3 I have shown a blank 6 of sheet metal which is slotted along the lines 7 at right angles to the general line of the blank and wings 8 are thereby produced, which wings are bent upward in Fig. 4, while other wings 9 are bent downward so as to produce 25 a structure such as shown in Figs. 4, 5 and 6, wherein wings 8 extend upwardly all parallel to each other from the edges of a zig-zag central strip 6 and other wings 9 extend downwardly, again all parallel to 30 each other and preferably at right angles to the planes of the upwardly extending tongues 8. The words "upwardly" and "downwardly" are used here merely relative to each other as it is absolutely immaterial whether the central portion 6 of the 35 insert is horizontal or vertical or at any desired angle to the horizontal or vertical. I wish further to point out that while I prefer the wings 8 and 9 to be at substantially right angles to the central plate 6, that the corners between the wings and the plate may be sharp or rounded, as may be desired, a rounded corner being preferred although the radius of the roundness should be small. 40 The outer edges of the wings are so curved 45 as to fit the inner surface of the conduit 5 and thus compel all of the gases to travel the helical and zig-zag paths.

Referring now to Fig. 4, and conceiving 50 the exhaust gases traveling from the right to the left, and also conceiving this insert mounted in a tube 5 as indicated in Fig. 5, the gases will strike the wing 8^a and be deflected transversely of the insert against the 55 interior surface of the conduit and be intercepted by the wing 8^b. As these gases cannot easily reverse their direction, they pass over the edge 6^a into the space on the other side of the plate 6. Those gases which enter 60 on the opposite or lower side of the plate 6 will strike a wing 9 and be deflected across the conduit, being guided by the next wing 9 which is parallel to the first. These gases, therefore, will move along the conduit until 65 they reach the edge 6^b where they will pass

to the upper side of the plate 6. Other portions of these gases will impinge upon the wing 9 just below the edge 6^c and be deflected upwardly thereby and then will pass along the conduit between the tongues 8^b and 70 8^c and again pass down over the edge 6^d and under the plate 6 just below the tongue 8^d.

The gases which rise along the lower edge of the wing 8^c and pass above the plate 6 will pass along between the wings 8^a and 75 8^b and then dip down over the edge 6^e. In other words, these wings will cause the gases which impinge thereon to strike against the interior surface of the conduit and also cause them to travel along the conduit in a helical path or rather in two helical paths. The individual amounts of the gases which flow through the exhaust conduit by reason of the explosions of the fuel in the engine are therefore intercepted to some extent, are 80 deflected by not only the wings of the insert but also by the inner surface of the exhaust conduit, and while a portion of them do not pass from one side of the insert to the other and therefore travel faster, the other portions are thus deflected into the helical paths and travel slower, the result being a reduction of the high pressure of the 85 exhaust impulses and an increase of pressure of the gases between such impulses until at the end of the insert the pressure of the stream of gas passing through the muffler is substantially uniform.

In Fig. 7 I have shown the wings 8 and 9 provided with openings 10 to permit some 90 of the gases to pass through and thus assist in the mixing of the gases in this muffler.

In Fig. 2 I have shown the exhaust manifold 2 provided with an insert 11 and I find that this construction is admirably adapted 100 for breaking up the small particles of fuel which are carried along by the air drawn into the engine from the carburetor 12. This result is principally attained by the air laden with the fuel particles striking the wings of the insert and being deflected thereby against the inner surface of the manifold so that after traveling but very few inches these particles are reduced to an impalpable mist, 105 which is the proper condition for the fuel of an internal combustion engine.

The details and proportions of the insert can be widely changed by those skilled in the art without departing from the spirit 110 of my invention as set forth in the following claims. The idea of causing the gases to travel in zig-zag and helical paths within the conduit because of the wings which have been sheared up from the central plate is 115 the fundamental idea of this invention, and because such inserts are sheared up from thin sheet metal and in themselves form but very little obstruction, the original speed of the exhaust gases is but very little reduced. 120 It will be understood that the helical paths 125

may be in either direction according to the positions of the wings. The checking down of the exhaust gases occurs toward the discharge end of this muffler and it is brought about by the reduction in the temperature and by the equalizing of the pressures. There is therefore very little liability of back pressure due to the insertion of these devices in the exhaust pipes of engines. The gases travel in the same direction at all times and for that reason flow more freely through these conduits than if they were doubled back on themselves and caused to change directions entirely. The friction within the muffler is almost negligible.

I claim:—

1. In a device of the character described, a sheet metal insert for cylindrical conduits comprising a flat central portion having slits at right angles to its edges and wings extending from opposite sides thereof and having their edges adapted to fit the inner surfaces of the conduits, said wings being staggered to intercept and deflect gases passing through such conduits, said wings extending from the plane of the sheet at either side of each slit along a line approximately forty-five degrees from said slit. 25
2. In a device of the character described, a sheet metal insert for cylindrical conduits comprising a flat central portion having slits at right angles to its edges and wings extending from opposite sides thereof and having their edges adapted to fit the inner surfaces of the conduits, said wings being staggered to intercept and deflect gases passing through such conduits, said wings extending from the plane of the sheet at either side of each slit along a line approximately forty-five degrees from said slit, said wings being perforated to permit the passage of gases. 30 35 40

JNO. D. TEMPLETON.
